UNITED STATES PATENT OFFICE

123,343

DESIGN FOR A WALLPAPER

William Ritchie, Jr., Clifton, N. J.

Application September 28, 1940, Serial No. 95,499

Term of patent 3½ years

To all whom it may concern:

Be it known that I, William Ritchie, Jr., a citizen of the United States of America, residing in Clifton, county of Passaic, and State of New Jersey, have invented a new, original, and ornamental Design for a Wallpaper, of which the following is a specification, reference being had to the accompanying drawing, forming part thereof, wherein the figure of the drawing is a plan view of a wallpaper showing my design.

I claim:

The ornamental design for a wallpaper, substantially as shown.

WILLIAM RITCHIE, JR.
